UNITED STATES PATENT OFFICE.

WILLIAM J. MACK, OF BUFFALO, NEW YORK.

DRAFT-RIGGING FOR RAILWAY-CARS.

No. 927,737.

Specification of Letters Patent.

Patented July 13, 1909.

Application filed November 22, 1906. Serial No. 344,593.

To all whom it may concern:

Be it known that I, WILLIAM J. MACK, a citizen of the United States, residing at Buffalo, in the county of Erie and State of New York, have invented certain new and useful Improvements in Draft-Riggings for Railway-Cars, of which the following is a specification.

This invention relates to railway rolling stock, and more especially to the draft rigging connected with cars and by which the draw-bars and couplings are supported, and the object of the same is to improve the construction of these parts so that they may be readily inspected or may be removed or repaired individually by disconnecting the least number of associated pieces.

The draft rigging herein described comprises broadly longitudinal sills, a continuous draft-bar between them, bolsters supporting them, draw-bars carried by the sills, spring connections between these elements and couplings attached to the draw-bars.

The drawings illustrate the device in detail at only one end of a car, but as shown in the general view in Figure 1, it is duplicated at the other end and the continuous draw-bar connects the two.

The parts herein described are by preference all of metal, although it is quite possible that some of these parts or others used in conjunction with them could be of other material. The exact size, shape, and proportion is immaterial; and the appended claims point out the novelty.

In the drawings,—Fig. 1 is a perspective view of my complete draft rigging. Figs. 2, 3, and 4 are plan views, side elevations, and bottom plan view respectively of one end of the device, the other end being an exact duplicate. Fig. 5 is a horizontal section taken on line 5—5, Fig. 3. Fig. 6 is a vertical section taken on line 6—6, Fig. 2. Figs. 7 to 12 are sections on the section lines 45 respectively indicated in Fig. 3. Fig. 13 is an enlarged perspective detail of the draw-bar. Fig. 14 is an enlarged perspective detail of the sills in their relative position. Figs. 15 and 16 are perspective details of 50 the top and bottom plates. Fig. 17 is a perspective detail of one follower.

The reference numeral 1 designates longitudinal sills which are preferably I-beams properly attached to and supported by the 55 car body in any practicable manner, and 2 is

a continuous draft-bar also in the form of an I-beam turned on edge so that its web is horizontal and it becomes in effect an H-beam. As usual, the draft bar extends the length of the car and connects the sills 60 at one end with those at the other, being secured to them by bolts 3. In addition to this attaching means there are stops 4 arranged at either side of each end of the draft-bar, held in place by said bolts 3, having inturned flanges 5 at their inner ends against which the end of the draft-bar abuts, and having out-turned flanges 6 at their other ends which pass over the extremities of the sills so as to take up the thrust of the 70 latter in case of shock and prevent cutting off the bolts 3.

I consider it of advantage to form both the sills and draft-bar of the shape described, and set their webs at right angles to each other, and I consider the stops of considerable advantage in the connection in which they are employed. The webs of the sills are provided at proper points with openings 7 for permitting inspection of 80 springs described below, their upper flanges are notched, as at 8, and the other parts are pierced with bolt holes at proper points for the attachment of the top and bottom plates 9 and 11, respectively, shown in Figs. 15 85 and 16. Referring also to Figs. 6 and 9, it will be seen that the top plate 9 has a rib 10 on its under side which sets into said notches in the upper flanges of the sills 1, and upon the webs of the latter; while the bottom 90 plate 11 has a rib 12 on its upper side of a length to fit between the webs of the sills, the lower flanges of the sills being cut-away at such points, as shown in Fig. 9. Said bottom plate has hooks 13 at its outer ends 95 which fit outside said flanges, the top plates thereby preventing the relative longitudinal displacement of the sills and the bottom plates their relative lateral displacement, and the inner faces of the webs and the two 100 ribs producing a rectangular opening which forms a housing for the body of the draw-bar.

The draw-bar (Fig. 13) has a body 20 which is preferably made of one piece, having a number of upright pockets 21 with inspection openings 27 in their side walls at points to register normally with those numbered 7 in the sills. At its rear end the top and bottom are cut away and its side plates 110

have openings so that a yoke 22 is produced, for a purpose to appear below. A pocket 23 is formed at the front end of the draw-bar and is boxed in or closed, at top and bottom 5 (Figs. 6, 10, and 18), and pierced vertically with a hole for a pivot bolt 24 by which the shank of a coupling 25 is held in place. This pivot bolt is preferably inserted from beneath, and has a head 26 at its lower end 10 resting upon a lip or extension 112 which projects forwardly from a front bottom plate 111 as seen in Figs. 4, 6 and 10, so that ordinarily the coupling will be held therein although it can be removed by unscrewing the front bottom plate 111 and thereby 15 removing the pivot bolt. Said forward pocket is also pierced laterally with oval holes 28 forward of those for the pivot bolt, and within these holes stands a transverse 20 oval bar or key 29 which may be held in place by upright pins 30 passing through the side walls of the boxing and adapted to be lifted out as shown in Fig. 11 when the oval bar or key is to be withdrawn. The latter passes through a hole in the coupling 25 which is oval in cross section and is enlarged 25 laterally at each end as seen in Fig. 5 thereby permitting the coupling to swing on the pivot-bolt, but utilizing the oval bar to afford 30 additional strength to the connection between. At the extreme front end of the draw-bar is an enlarged head 31 having interior sockets for springs 32 (Fig. 12) which stand at each side of the shank of the 35 coupling 25 so as to hold it normally centered. These sockets are closed at their outer ends by plates 33, which when removed give access to the springs 32. Within the head beneath the opening for the draw- 40 bar is a shallow depression 34 in which move balls or rollers 35 that support the shank of the coupling and permit it to move from side to side with the least possible friction. Access to this depression and the rollers can 45 of course be had by removing the coupling. Thus the various parts of the connection between the coupling and draw-bar are readily accessible without the use of tools which may be rare, and without disturbing other 50 parts of the rigging; while the coupling stands normally centered, supported on balls or rollers, and is permitted the necessary movement to either side. I show no details of the coupling itself, as that element forms 55 no part of the present invention.

Springs are located in the pockets of the draw-bar. Three are illustrated herein, and as they are similar in construction I will describe but one, see Figs. 5, 6, 8, and 17. The 60 spring itself, 40, is here shown as an expansive coil whose ends fit in sockets 42 formed in the inner faces of twin followers 43, there being notches 47 to form side openings to register with those numbered 27 and 7 to 65 permit inspection of the springs. Each

follower is of a width to fit transversely within a pocket 21 in the draw-bar, but has top and bottom flanges 44 which project above and below partitions 45 between said pockets and rest against the ribs 10 and 12 70 of the top and bottom plates. Hence when the parts are in their normal position (Fig. 6) the springs expand and hold the followers against the partitions and their flanges 75 against said ribs, and the registering openings permit inspection. A forward pull on the draw-bar carries the partitions forward, and they move the rearward followers toward the forward followers, which latter are held by the ribs; and conversely a rearward 80 movement of the draw-bar will similarly compress the springs in a manner which will be clear. To remove any spring, it is necessary to remove two bottom plates which support its followers, and draw the followers 85 and spring downward out of their pocket; and the same or similar members can be replaced by a reverse operation. In some cases, or if there are a number of pockets and springs, a buffer spring described below 90 might be omitted, but I have shown and prefer its use.

The buffer spring 50 is also a coiled expansion spring located between the sills and between plates 51 and 52 which fit loosely 95 between the sills Figs. 5 and 6 and are supported on a wide bottom plate 113 having ribs 114 on its upper face which bear against the webs of the sills, the inner lower flanges of the latter being cut-away for this purpose, as shown in Fig. 7. The inner plate rests against the flanges 5 of the stops 4, while the outer plate rests against the end of the yoke 22 of the draw-bar. Hence this strong buffer spring will resist powerful end 100 thrusts of the draw bar and prevent the breaking of parts. It may be removed by withdrawing the bottom plate 113 and taking it out with its plates 51, and can be replaced by a reverse operation, both without 105 disturbing other parts of the draft rigging.

A bolster 60 is held to the sills by bolts 64 passing outwardly through the latter and through a part of the bolster. By removing said bolts, the position of the bolster on the 110 sills can be changed.

Having thus described my invention, what I claim is,—

1. In a draft-rigging, the combination with a housing having a forward extension 120 at its bottom, and a draw-bar mounted in said housing and having a pocket in its front end; of a coupling whose shank enters the pocket, and a pivot-bolt through said shank and the top and bottom walls of the pocket 125 and having a head at its lower end resting normally on said extension.

2. In a draft rigging, the combination with a housing, and a draw-bar mounted therein and having a pocket in its front end 130

5 pierced vertically and horizontally; of a coupling whose shank fits loosely in the pocket and is pierced vertically and horizontally with holes of which the latter is laterally enlarged at each end, a pivot-bolt through the vertical holes, a key through the horizontal holes, and means for holding the pivot bolt and bar in place.

3. In a draft rigging, the combination with 10 a housing, and a draw-bar mounted therein and having a pocket in its front end, the draw-bar being pierced vertically with a round hole for a pivot bolt, horizontally with an oval hole forward of that for the 15 pivot bolt, and vertically through its side-walls with small holes intersecting the oval hole; of a coupling whose shank fits the pocket loosely and is pierced with a vertical and with a horizontal oval hole which latter 20 is laterally enlarged at each end, a pivot-bolt in the vertical hole, means for holding said pivot-bolt in place, an oval key having eyes near its extremities and fitting said oval hole in the pocket and passing through that 25 in the coupling, and pins in said small holes passing through the eyes in said key.

4. In a draft rigging, the combination with a housing, a draw-bar mounted therein and having a pocket in its front end, and a 30 head surrounding said front end and having sockets opening through its sides; of a coupling whose shank loosely fits said pocket, a pivot-bolt, springs in the sockets at either side of the shank, and plates at 35 the exterior of said head holding said springs removably in place.

5. In a draft rigging, the combination with a housing, a draw-bar mounted therein and having a pocket in its front end, and a 40 head surrounding said front end and having sockets opening through its sides; of a coupling whose shank loosely fits said pocket, a pivot-bolt, springs in the sockets at either side of the shank, plates at the exterior of the head holding said springs 45 removably in place, and rolling supports within the head beneath the draw-bar.

6. In a draft rigging, the combination with a housing, a draw-bar therein having 50 a pocket in its front end, and an enlarged head around said front end having a depression at the lower side of said pocket; of a coupling whose shank fits loosely in the pocket, a pivot-bolt, and rolling supports 55 mounted in said depression beneath said shank.

7. In a draft rigging, the combination with a housing, a draw-bar therein having 60 a pocket in its front end, and an enlarged head around said front end having a depression at the lower side of said pocket; of a coupling whose shank fits loosely in the pocket, an upright pivot-bolt holding it therein, a horizontal key across the pocket 65 and passing loosely through said shank,

means for centering the latter in the pocket, and rolling supports mounted in said depression beneath said shank.

8. In a draft rigging, the combination with a draw-bar having upright pockets 70 with partitions between them, and within each pocket a spring and two follower plates having top and bottom flanges projecting beyond the contour of the draw-bar; of a housing for the latter comprising parallel 75 I-beams between whose webs and flanges said draw-bar fits, and top and bottom plates bolted across said I-beams and having ribs separating the flanges on the followers and standing in line with the partitions in the 80 draw-bar when the latter is in its normal position.

9. In a draft rigging, the combination with a draw-bar having upright pockets 85 with partitions between them and openings in their side-walls, and within each pocket a spring and two follower plates having top and bottom flanges projecting beyond the contour of the draw-bar; of a housing for the latter comprising parallel I-beams between 90 whose webs and flanges said draw-bar fits, the upper flanges being notched and the webs having openings adapted to register with those in the draw-bar, top and bottom plates bolted across said I-beams, ribs on the 95 top plate entering said notches, shorter ribs on the bottom plates fitting between the lower flanges of the I-beams, and hooks on these plates fitting outside said flanges, said ribs separating the flanges of the followers 100 and standing in line with the partitions in the draw-bar when the latter is in its normal position.

10. In a draft rigging, the combination with a draw-bar having upright pockets 105 with partitions between them and openings in their side walls, and within each pocket a spring and two follower plates, each plate having a socket for the spring, and notches adapted to register with said openings in 110 the side walls, and top and bottom flanges; of a housing comprising parallel I-beams between whose webs and flanges said draw-bar fits, the webs having openings adapted to register with those in the side walls of 115 the draw-bar, and top and bottom plates connecting the flanges on the I-beams and interposed between those on the followers.

11. In a draft rigging, the combination with a housing comprising parallel sills having inwardly projecting top and bottom flanges, and plates secured across them and having ribs standing in the planes of the flange; of a hollow draw-bar guided between said sills and the flanges on the latter, 120 transverse partitions in the draw-bar forming pockets open at top and bottom, within each pocket a spring and two follower plates, the latter being of the width of the 125 pocket but of greater height than the depth 130

of the pocket so as to engage the ribs on the plates of the housing.

12. In a draft rigging, the combination with a draw-bar having a yoke at its rear end, a housing for the draw-bar, springs in the latter, and stops for the springs carried by the housing; of supports for the housing, a continuous draft bar between the housing at one end of the car and that at the other, 10 stops interposed between the rear end of each housing and the adjacent end of the draft-bar, and buffer springs interposed between the latter and said yoke.

13. In a draft rigging, the combination 15 with a draw-bar, and a housing therefor comprising parallel I-beams whose webs stand vertical; of a continuous draft-bar consisting of an H-beam whose flanges fit between the webs of said I-beams at each 20 end of the car, and connections between these members.

14. In a draft rigging, the combination 25 with a draw-bar, and a housing therefor comprising parallel I-beams whose webs stand vertical; of a continuous draft-bar 30 consisting of an H-beam whose flanges fit between the webs of said I-beams at each end of the car and stops comprising bodies interposed between the flanges of the continuous draft bar and the webs of the I-beams and flanges fitting over the ends of these members, respectively.

15. In a draft rigging, the combination 35 with a draw-bar, having pockets in its body, a housing therefor consisting of parallel I-beams, stops across the latter, and springs in said pockets against said stops; of stops at the inner end of the housing, plates within the latter against said stops and against the 40 rear end of the draw-bar, a buffer spring between said plates, and a supporting plate for this spring bolted to the bottom of said housing.

16. In a draft rigging, the combination 45 with a draw-bar, a housing therefor consisting of parallel I-beams, stops across the latter, and springs and follower plates carried by the draw-bar and engaging said stops; of stops between the rear ends of said 50 I-beams, a plate resting against them, another plate against the inner end of the draw-bar, these plates being supported by the flanges of the I-beams, a buffer spring between said plates, and a wide bottom plate 55 bolted to the lower flanges of said I-beams and supporting said spring.

17. In a draft rigging, the combination 60 with a draw-bar, having a yoke at its rear end cut away at its top and bottom and provided with openings in its side plates, a

housing for the draw-bar, and springs between these members; of a transverse bolster comprising members crossing the housing at points opposite the normal position of the yoke and there perforated for the purpose set forth, stops at the inner end of the housing, and a buffer spring between said stops and the inner end of the yoke. 65

18. In a draft rigging, the combination of a draw-bar having pockets with partitions 70 between them, and within each pocket a spring and two followers; of a support for the draw-bar, and detachable stops on said support in line with the partitions in the draw-bar and fitting between adjacent followers in adjoining pockets. 75

19. In a draft rigging, the combination with the sills, of a draw-bar movable between said sills and having upright pockets 80 with partitions between them, and within each pocket a spring and two follower plates extending beyond the contour of the draw-bar, and stops detachably secured to said sills in line with said partitions in the draw-bar and fitting between the extending portions of the follower plates, each stop fitting between adjacent follower-plates in adjoining pockets. 85

20. In a draft-rigging, the combination 90 with a housing, and a draw-bar mounted in said housing, a coupling, a pivot-bolt fastening said coupling to said draw-bar and having a head at its lower end, and means to retain said pivot-bolt in place and on displacement of which said pivot-bolt may be 95 withdrawn to detach the coupling.

21. In a draft-rigging, the combination 100 with a housing, and a draw-bar mounted in said housing, a coupling, a pivot-bolt fastening said coupling to said draw-bar and having a head at its lower end, and a plate detachably secured to the housing on which the head of said pivot-bolt rests.

22. In a draft-rigging, the combination 105 with a housing of a draw bar having an upright-pocket, a spring and followers within said pocket, stops on said housing against which said followers bear, and a plate detachably held to the underside of the housing allowing the removal of said spring and 110 followers from said pocket when detached from said housing.

In testimony whereof, I have affixed my signature in the presence of two subscribing witnesses.

WILLIAM J. MACK.
